UNITED STATES PATENT OFFICE

97,850

DESIGN FOR A CIGARETTE CASE

Winthrop M. Jones, Philadelphia, Pa.

Application February 23, 1935, Serial No. 55,570

Term of patent 3½ years

To all whom it may concern:

Be it known that I, Winthrop M. Jones, a citizen of the United States, residing at the city and county of Philadelphia, and State of Pennsylvania, have invented a new, original, and ornamental Design for a Cigarette Case, of which the following is a specification, reference being had to the accompanying drawing, forming part thereof.

In the drawing,

I claim:

The ornamental design for a cigarette case, as shown.

In testimony whereof I affix my signature hereto.

WINTHROP M. JONES.
